MERRICK D. MARCY, OF WORCESTER, MASSACHUSETTS.

Letters Patent No. 94,122, dated August 24, 1869.

IMPROVEMENT IN MACHINES FOR MAKING BOLT-HEADS.

The Schedule referred to in these Letters Patent and making part of the same.

To all persons to whom these presents may come:

Be it known that I, MERRICK D. MARCY, of the city and county of Worcester, and State of Massachusetts, have invented a new and useful or improved Machine for Heading Bolts; and I do hereby declare the same to be fully described in the following specification, and represented in the accompanying drawings, of which—

Figure 1 is a front elevation;

Figure 2, a side view;

Figure 3, a longitudinal section; and

Figure 4, a transverse section of it.

Figure 5 is a top view of the bed and the movable die or bolt-holder.

The nature of my invention consists in combining with the bed, the bolt-holder, the hammers, and the upsetting-mechanism, a mechanism for gradually raising the bed while the bolt is being headed.

Also, in combining therewith a mechanism for causing the sudden depression of the bed after the heading of the bolt may have been completed.

Also, in the combination of the movable die or bolt-blank carrier with the bed, by a peculiar holding mechanism, as hereinafter explained.

In the drawings—

A denotes the bed, which, in form, is the frustum of a wedge.

This bed rests with its longer side upon that of a similar frustum or wedge, which is supported upon and by two parallel guides or rails, C C, fixed to the upper surface of a base-plate, D.

There is another pair of such guides, E E, fixed on the upper surface of the wedge B, and made to enter corresponding grooves formed in the bed A.

Furthermore, the said bed A has two ears or projections *a a* extended from opposite sides of it, and into vertical grooves *b b* of a frame, F, elevated on the base-plate.

Within this frame, and applied to it so as to be capable of sliding vertically, is the upsetter G, which is operated by an eccentric, *d*, fixed on a horizontal shaft, *e*, the said shaft being duly supported by the frame F.

A T-piece embraces the eccentric, and is jointed to the upper end of the upsetter.

Around the shaft and a pulley, *g*, fixed on a shaft, *h*, a cross-band, *i*, plays.

The shaft *h* carries a pinion, *i*, to work in a rack, *k*, fixed to the side of the wedge B, the purpose of the belt, the pulley, the shaft, the gear, and rack, being to feed the wedge B along underneath, and so as to gradually elevate the bed.

The said bed has an elongated passage, *l*, made down through it, and over a similar passage, *m*, extending down through the wedge B.

Resting on the upper part of such passage, and within a circular rebate, *n*, formed in the bed, is the bolt-die or carrier H, which is flanged, as shown at *o*, to rest on the upper surface of the bed.

This bolt-die holds the bolt *s* while it is in the act of being headed.

From the flange of the said die, two arms, *p q*, extend in opposite directions, and, by being moved under two cleats, *r s*, serve, with such cleats, to hold the bolt-die in place upon the bed.

Each of the arms, where it goes underneath its cleats, is bevelled or wedged laterally, so as to fit closely thereto.

There is pivoted to the frame F, four curved levers or hammers, *I I*, *K K*, each having an adjustable steel die or hammer heat, *t*, fixed to its lower part.

To the upper ends of these levers, toggles or connections, *L L*, *M M*, are jointed, such toggles being also jointed to the upsetter.

The joints of one pair of the said toggles, and the upsetter, are arranged over those of the other pair, so that when the toggles of the first pair are horizontal, those of the other will be at an acute angle with each other.

This arrangement causes the pairs of hammers, through the action of the upsetter and toggles, to operate alternately and not simultaneously on the bolt-head.

By the connection of the hammer-levers with the upsetter, by means of the toggles or connections *L L*, *M M*, the said levers will be moved or swung on their fulcrum, by the upsetter operating with such toggles, the same causing two of the hammers to approach each other, and strike and compress the bolt-head at once on two opposite sides, after which they will recede from it, and the other two hammers will move up to, and strike and compress the bolt-head on its other two opposite sides.

The upsetter strikes down upon the head and flattens it; or spreads it out, or upsets it, the head being gradually raised until it may be completed by the upsetter and the successive blows of the hammers.

We combine with the machine means or mechanism for causing the sudden depression of the bed, immediately after the completion of the bolt-head, the same being in order to enable the bolt-die or carrier to be removed, and the bolt to be discharged from it, and another bolt to be put in the place of it.

To this end, we attach to the elevating-wedge, by means of a line, *t*, going over a pulley, *u*, a weight, *v*, which, as soon as the bolt-head may be completed, and the pulley *g* be unclutched from its shaft, will suddenly draw back the wedge, and cause the depression of the bed.

To enable the wedge to be retracted, the said pul-

ley g should be applied to the shaft h , so as to be capable of being slid endwise thereon, both toward and away from a clutch, w , fixed on such shaft, the pulley being provided with recesses x , to receive the clutch.

The pulley may be moved up to or away from the clutch, by means of a forked lever, suitably applied to a groove, y , in the hub of the pulley.

I claim—

1. In combination with the bed A , the bolt-holder H , the upsetter G , and the series of hammers $I I$, $K K$, provided with mechanism for operating them, as explained, a mechanism for gradually raising the bed, while the bolt is being headed, such mechanism consisting of the wedge B , and the rack h , and pinion i , or the equivalent thereof, for moving such wedge underneath the bed.

2. Also, in combination with the bed A , the bolt-holder H , the upsetter G , the hammers $I I$, $K K$, and the wedge, or mechanism for raising the bed, as and for the purpose described, a mechanism for causing the sudden depression of the bed, immediately after the heading of the bolt may have taken place, such mechanism being not only a weight, v , connected to the bed by a line, t , going over a pulley, u , but a clutch, w , or means of engaging and disengaging the driving-pulley g of the pinion-shaft h with such shaft, as described.

MERRICK D. MARCY.
